UNITED STATES PATENT OFFICE.

JOHN J. CANNAN, OF ROCHESTER, NEW YORK, ASSIGNOR TO HENRY LIKLY & COMPANY, OF ROCHESTER, NEW YORK, A CORPORATION OF NEW YORK.

WARDROBE-TRUNK.

No. 858,572.

Specification of Letters Patent.

Patented July 2, 1907.

Application filed October 29, 1906. Serial No. 340,954.

To all whom it may concern:

Be it known that I, JOHN J. CANNAN, of Rochester, in the county of Monroe and State of New York, have invented certain new and useful Improvements in Wardrobe-Trunks; and I do hereby declare the following to be a full, clear, and exact description of the same, reference being had to the accompanying drawings, forming a part of this specification, and to the reference-numerals marked thereon.

10 My present invention relates to improvements in trunks, and has reference more especially to those of the type especially adapted to be employed as receptacles for outer garments, and the object of the present invention is to provide a trunk of this class having devices of an improved construction and arrangement for supporting wearing apparel such as clothing and other garments, and which is so divided that it may be employed wholly as a garment receptacle, or it may be converted into a combination arrangement by the application of a suitable cabinet adapted to contain toilet articles, linen and other articles which may be inclosed in a small space, novel devices being provided by means of which this cabinet may be readily applied or removed from the trunk, the latter being thereby adapted to use either wholly as a garment receptacle for the transportation and exhibition of clothing and other garments; or as an ordinary traveler's trunk adapted to contain garments as well as other accessories useful to the traveler.

20 To these and other ends the invention consists in certain improvements and combinations of parts, all as will be hereinafter more fully explained, the novel features being pointed out in the claims at the end of the specification.

25 In the drawings: Figure 1 represents a vertical section of a wardrobe trunk constructed in accordance with my invention, showing the garment-supporting devices and the cabinet in combination. Fig. 2 represents a horizontal section on the line 2—2 of Fig. 1, one 30 of the doors of the trunk being shown in open position, and the respective garment-supporting slide withdrawn. Fig. 3 is a perspective view of the detachable cabinet removed from the trunk. Fig. 4 shows the method of applying and removing the cabinet relatively to the trunk, and Fig. 5 is a detail view of the handle employed on the top of the trunk.

Similar reference numerals in the several figures indicate similar parts.

35 The present embodiment of my invention comprises generally, a box or casing 1, preferably of a height sufficient to enable the garments to be suspended full length therein, and having a bottom, supported upon a set of casters or other suitable supports 3, sides 4 and the top 5, the latter being preferably surmounted by a handle

or projection 6 of such a height as will prevent the trunk from being placed in an inverted position. Between the sides, and the top and bottom of the trunk is fitted a transverse partition 7, which serves to divide the interior space of the trunk into two separate compartments, and access to the latter is controlled by the doors 8 and 9 respectively, the latter being supported on hinges 10 and 11 arranged on the trunk sides, so that these doors will swing preferably in a horizontal plane, a roller 12 being provided, if desired, on the unsupported edge of each door and adapted to ride on the floor to prevent sagging of the door.

In order to effectually seal the joints formed between the meeting edges of the trunk proper and the doors, I prefer to employ a sealing strip 13 at the inner side of the trunk opposite to the usual metallic band 14 which serves to cover the joint from the exterior, the sealing strip being attached to one of the relatively movable parts such as the door, and embodying a strip of leather, felt or other flexible material, doubled longitudinally about a cord or wire 15, this cord or wire serving to form the doubled edge of the strip into a roll which is free or unattached and adapted to overlap the adjacent inner edge or wall of the trunk, the doubled or folded portions of the strip being secured to that part of the trunk which is opposite to that part of the trunk with which the roll or yielding portion of the strip is arranged to overlap. A device of this kind, by reason of its yielding or resilient properties, will effectually seal the joint between the door and the trunk proper, and will thus exclude dust, dampness and insects.

85 In the upper part of the trunk are arranged suitable devices for supporting the garments, and in order to enable both compartments of the trunk to be employed, if desired, as a garment container, a garment-supporting slide is provided for each compartment, and these slides are so constructed and arranged that while they are being employed for sustaining the garments, they may be drawn out to render the garment conveniently accessible for inspection or removal and replacing, and when the trunk is closed, they may be compactly arranged 90 within the trunk. The garment-supporting slides, in the present instance, are substantially duplicates, the slide 16 being adapted to be withdrawn from one of the compartments, while the slide 17 is arranged to be withdrawn in an opposite direction from the other compartment. Each of these slides is composed of a rod or tube doubled intermediately to form a loop 18 which is adapted to serve as a handle at the forward end of the slide to facilitate manipulation thereof, and the extensions beyond the looped portions are arranged substantially parallel to form a pair of guide rails 19 and 20, and between the guide rails is arranged an intermediate supporting rail 21 which is adapted to coöperate with

the hooks 22 of the garment hangers 23, one end of this supporting rail being secured to the handle or looped portion of the slide, while its opposite end is provided with a removable nut or limiting projection 24. These 5 slides may be mounted in any appropriate manner, but it is preferable to provide a telescoping or interfolding arrangement which will economize the space in the trunk, and a mounting of this kind is shown in the present embodiment, comprising an intermediate or 10 center bearing member 25 made up of a bar secured to the under side of the top of the trunk by screws or other suitable means and provided with a set of transversely-arranged apertures 26 of a size and arrangement corresponding to the diameter and spacing of the guide and 15 supporting rails of the slides, the limiting projections 24, on the slides being arranged to coöperate with the corresponding sides of the intermediate bearing to limit the withdrawing movement of the slides, complete withdrawal of the latter being permitted by removal of this 20 nut or projection. On the opposite sides of this center bearing are provided a pair of outer bearings 27 and 28, these bearings comprising blocks suitably secured to the top of the trunk in a manner similar to that described for the center bearing, the bearings 27 coöperating 25 with the guide rails of the slide 16, and the bearings 28 coöperating with the corresponding rails of the slide 17 to sustain the weight imposed upon these slides when they are in withdrawn position. These slides are 30 so constructed that garment hangers of various forms may be suspended therefrom and adjusted longitudinally thereof, and of course the garments and other articles of apparel are held in suspended position from these hangers, and in order to prevent the disarrangement of the garments when the trunk occupies a position other than the vertical, it is preferable to employ 35 a compressor or follower, embodying generally, a substantially rigid frame-work 29 suspended from the supporting rail of the slide by the snap hook 30 and having tightening straps 31 for pressing it against the garments 40 to hold them in proper arrangement.

The novel arrangement of slides described enables both compartments to be employed as a container for garments, and a trunk constructed in this way is well adapted to the purposes and requirements of salesmen 45 and those carrying a line of samples of clothing and other garments which should be kept carefully folded and supported by suitable hangers, and which may be conveniently accessible for exhibition, but the present invention enables the trunk to be converted into a 50 combination arrangement wherein one compartment is reserved exclusively for the suspended garments, and the other compartment is adapted, both as a garment receptacle and to receive a cabinet which may be employed for other purposes, the cabinet shown being 55 adapted to contain toilet articles and other devices of a nature that would permit them to occupy comparatively small space, or such devices as may be placed in drawers, the detachable arrangement of the cabinet enabling the latter when removed from the trunk, to be 60 employed as a dresser, or for exhibition and other purposes. This cabinet in the present instance, embodies a rectangular casing 32 open at one side and fitted with a set of brackets or slides 33 for supporting a set of 65 drawers 34, the latter, when the cabinet is in position within the trunk, being so arranged, of course, that

when the appropriate door of the trunk is open, these drawers are accessible.

Any appropriate devices may be employed for detachably mounting the cabinet securely within the trunk, the devices employed in the present instance 70 embodying a pair of lower attaching members 35, one of each being secured to the lower rear portion of the cabinet and provided with a vertical slot 36 therein arranged to enter from above and coöperate with a correspondingly-arranged supporting projection 37 on the 75 inner side of the trunk, and the upper attaching members 38 secured to the sides of the cabinet toward the top thereof, and provided with a forwardly and upwardly extending slot 39, adapted to receive the corresponding projections 40 arranged on the sides of the 80 trunk by a relative tilting movement of the upper portion of the cabinet in a direction first rearwardly, while the lower projections 37 are resting at the openings of the slots 36 in the lower attaching devices, and then by downward movement, which enables the projections 85 37 and 40 to enter and coöperate with the upper ends of the vertical slots in the attaching devices, the cabinet being thereby supported within the trunk and held from lateral displacement by means of the angular slots in the upper attaching devices, and by reason of 90 the fact that the casing rests firmly against the partition 7 of the trunk, but of course this partition, if desired, may be omitted, the rear wall of the cabinet serving as a backing for the garments arranged in the opposite side of the trunk.

It is preferable to provide a large and substantial handle on the top of a trunk of this kind which will not only serve as a convenient grip for the baggage or others handling the trunk, but to prevent the trunk from being inadvertently stood in an inverted position, 100 as this would disarrange the garments contained by the trunk, and the handle shown in the present embodiment of the invention comprises a pair of end pieces or attaching members 41 and 42, each of the latter embodying an upwardly-projecting body portion 105 43 having a set of legs or attaching lugs 44, of any suitable number, three being preferable as they accommodate themselves to the surface to which they are applied, and the end pieces are secured to the trunk by the means of screws or rivets 45 extending into the top 110 of the trunk. Each end piece or attaching member is provided with an aperture 46 which is formed in the body portion of the member preferably at a point adjacent to where one of the legs or attaching lugs 44 adjoins, and in these apertures rests the ends of a connecting member 47 which serves as a handle for the grasp of the hand, this handle being made of any suitable material, although hard wood may be used to advantage, and it may fit either rotatably or firmly in the apertures of the end pieces, a firm fit being generally preferred.

A handle of the kind described may be cheaply constructed, and is well adapted to the purposes intended, as it is sufficiently strong to withstand the blows to which appliances of this kind are subjected.

A convertible trunk constructed in accordance with my invention is especially adapted to the needs of salesmen, as well as the ordinary traveler, the improved construction and arrangement of the garment-supporting slides enabling either a part or the whole of 130

the trunk to be utilized as a garment receptacle from which the garments may be reached in the most convenient way, and the cabinet and its supporting devices enables the trunk to be altered so that the space 5 thereof is appropriated to the best advantage, to the purposes of the usual traveler.

I claim as my invention:

1. In a wardrobe trunk, the combination with a trunk casing having door openings at its opposite sides, of two slides adapted to support garments and arranged to be moved outwardly in opposite directions, a guide located centrally of the trunk and supporting the inner ends of both slides and separate bearing numbers also supporting the slides and arranged at opposite sides of the guide. 10
2. In a wardrobe trunk, the combination with a casing, guides depending from the top of the casing and a garment supporting slide comprising side rails supported in the guides and an intermediate rail arranged in the plane of the side rails. 15
3. In a wardrobe trunk, the combination with a casing having door openings at its opposite sides, and a partition wall dividing it into two compartments, of two garment supporting slides each arranged with its outer end in one compartment and its rear end in the other compartment 20 and guides in the casing supporting the slides.
4. In a wardrobe trunk, the combination with the trunk casing having a garment compartment therein, and an opening for permitting access thereto, of a garment-supporting slide adapted to be withdrawn from said compartment through said opening and embodying a member having a pair of parallel guide rails, an intermediate garment-supporting portion, a handle portion connecting the forward ends of the guide rails, and bearings co-operating with the guide rails for slidably supporting the slide. 25
5. In a wardrobe trunk, the combination with the trunk casing having a garment compartment therein and an opening for affording access thereto, of an adjustable garment-supporting member adapted to be extended or withdrawn through said opening and embodying a bar doubled to form outer guide rails and forming a loop or bend at the forward end of the slide adapted to serve as a handle, and a garment-supporting portion on the member and bearings supported on the trunk for slidably mounting the garment-supporting member. 35
6. In a wardrobe trunk, the combination with the trunk casing having a garment compartment therein and an opening for affording access thereto, of a garment-supporting slide for said compartment embodying a pair of parallel guide rails, an intermediate looped portion connecting said rails and adapted to serve as a handle for operating the slide, an intermediate garment-supporting rail arranged between the guide rails, and bearings co-operating with the guide rails for adjustably supporting the slide. 45
7. In a wardrobe trunk, the combination with the trunk casing having means of access at the opposite sides thereof, of a pair of garment-supporting slides adjustable in opposite directions toward the respective means of access, each slide embodying a pair of guide rails, and a garment-supporting rail arranged intermediately of the guide rails, an intermediate bearing arranged to co-operate with the rails of both slides, and a pair of bearings ar- 55
- ranged at each side of the intermediate bearing and co-operating with the guide rails of the respective slide. 60
8. In a wardrobe trunk, the combination with the trunk casing having a garment compartment therein, of an extensible garment-supporting slide embodying a pair of guide rails, a connecting portion between the said rails adapted to serve as an operating handle at the forward end of the slide, a rail arranged intermediate of the guide 70 rails and adapted to serve as a support for the suspension of garment-supporting devices, bearings for adjustably supporting the slide, and a device co-operating with one of the bearings for limiting the movement of the slide in one direction. 75
9. In a wardrobe trunk, the combination with a casing open at its opposite sides and a cabinet removably mounted in one side of the casing, of two garment supporting slides located above the cabinet each extending the full width of the casing and movable outwardly therefrom in opposite directions. 80
10. In a wardrobe trunk, the combination with a casing having door openings at its opposite sides, and a cabinet arranged therein and accessible through one of the openings, of a garment supporting frame extending the full width of the casing and projecting over said cabinet and movable outwardly through the other opening in said casing. 85
11. In a wardrobe trunk, the combination with the trunk body or casing having openings in the opposite sides thereof, of adjustable garment-supporting devices mounted in the casing and adapted to be withdrawn in relatively opposite directions through the openings in the casings, and a cabinet adapted to removably fit into a portion of the casing and accessible through one of said openings. 90
12. In a trunk, the combination with the body or casing thereof, and projections suitably arranged therein, of a cabinet adapted to removably fit into the said casing, and devices thereon adapted to co-operate with the said projections in the casing to detachably secure the cabinet in position therein. 95
13. In a trunk, the combination with the body or casing thereof, and inwardly-extending projections arranged on the vertical sides thereof, of a cabinet adapted to fit into the said casing, and attaching members arranged on the vertical sides thereof and having slots therein adapted to co-operate with the said projections to detachably secure the cabinet in position within the cabinet, and a door for controlling access to the cabinet. 100
14. In a trunk, the combination with the body or casing thereof, and pairs of upper and lower projections extending inwardly from the vertical sides thereof, of a cabinet adapted to fit into the casing, a pair of attaching devices secured to the sides of the cabinet and having vertical slots adapted to receive the lower pair of projections of the casing by a relatively downward movement of the cabinet, and a pair of upper attaching devices arranged on the sides of the cabinet having angular slots therein extending relatively forwardly and upwardly, and adapted to receive the upper pair of projections of the casing by a relative movement of the upper portion of the cabinet first rearwardly and thence downwardly. 110
15. JOHN J. CANNAN.
